(57) **CLAIM**

The ornamental design for a watch face, as shown and described.

DESCRIPTION

FIG. 1 is a perspective view of a first embodiment of a watch face showing the new design;

FIG. 2 is a front elevation view thereof, the rear elevation view is comprised of unclaimed subject matter;

FIG. 3 is a top plan view thereof;

FIG. 4 is a right elevation thereof;

FIG. 5 is a bottom plan view thereof; and

FIG. 6 is a left elevation view thereof;

FIG. 7 is a perspective view of a watch face showing a second embodiment of the new design;

FIG. 8 is a front elevation view thereof, the rear elevation view is comprised of unclaimed subject matter;

FIG. 9 is a top plan view thereof;

FIG. 10 is a right elevation thereof;

FIG. 11 is a bottom plan view thereof; and

FIG. 12 is a left elevation view thereof;

FIG. 13 is a perspective view of a watch face showing a third embodiment of the new design;

FIG. 14 is a front elevation view thereof, the rear elevation view is comprised of unclaimed subject matter;

FIG. 15 is a top plan view thereof;

FIG. 16 is a right elevation thereof;

FIG. 17 is a bottom plan view thereof; and,

FIG. 18 is a left elevation view thereof.
